(57) **CLAIM**

The ornamental design for a whistle cleaning device, as shown and described.

DESCRIPTION

FIG. 1 is a top plan view of a whistle cleaning device showing my new design;

FIG. 2 is a front elevational view thereof;

FIG. 3 is a bottom plan view thereof;

FIG. 4 is a right side elevational view, the right side being a mirror image thereof;

FIG. 5 is a rear elevational plan view thereof;

FIG. 6 is a rear perspective view thereof; and,

FIG. 7 is a top perspective view thereof shown in an open configuration.

The broken line showing of details in FIGS. 3 and 7 are included for the purpose of showing environmental portions of the whistle cleaning device and forms no part of the claimed design.

1 Claim, 7 Drawing Sheets
